UNITED STATES PATENT OFFICE

2,460,894

AUTOMATIC MANURE CONVEYER

Nicholas Martinovich, Berlin Center, Ohio

Application July 8, 1947, Serial No. 759,495

7 Claims. (Cl. 214—89)

1

This invention relates to improvements in automatic manure conveyors for barns or stables.

An object of the invention is to provide an improved automatic manure conveyor for barns or stables including a sloping gutter formed in the barn or stable floor to the rear of the usual cow stanchions, whereby the manure may be readily conveyed by an endless chain conveyor built in said gutter and dumped into a carrier positioned in a pit formed at the end of the barn or stable, and said carrier, after being filled, being adapted to be elevated from said pit and moved along an overhead trackway to a manure dump pile in the barn yard.

Another object of the invention is to provide an improved built-in manure collecting gutter construction in a barn or stable, together with an endless conveyor mechanism disposed therein being operable by an electric motor and pump jack in connection with a ratchet wheel and cooperating alternately operated pivoted dogs or pawls, whereby the manure swept into the gutter will be automatically removed therefrom into a carrier and moved to a manure dump pile in the barnyard at a point remote from the barn or stable.

A further object of the invention is to provide an improved, self-draining gutter and automatic manure conveyor construction for a barn or stable which will be highly efficient in operation, and relatively inexpensive to manufacture and produce.

Other objects will appear as the description proceeds.

In the accompanying drawings which form a part of this application,

Figure 1 is a plan view partly in section of a barn or stable equipped with the improved automatic manure conveyor;

Figure 2 is a vertical longitudinal sectional view through a barn or stable showing the automatic manure conveyor built therein and the carrier and overhead trackway associated with the pit formed at the end of said barn or stable;

Figure 3 is a sectional view taken on the line 3—3 of Figure 2; and

Figure 4 is a side elevation of the electric motor driven pump jack and pawl and ratchet mechanism employed for operating the automatic manure conveyor.

Like characters of reference are used throughout the following specification and the accompanying drawings to designate corresponding parts.

In carrying out the invention, there is shown

5 a barn or stable having side and end walls 1 and 2 respectively, and an opening or doorway 3 through one end thereof, through which the automatic manure conveyor, later to be described, will extend.

10 A concrete pit 4 will be formed at the end of the barn or stable directly below the discharge end of said automatic manure conveyor.

A plurality of stanchions 5 will be built into the barn or stable, and a concrete floor 6 will be provided therefor.

An improved form of gutter construction generally denoted by the reference numeral 7 will be disposed longitudinally of the barn or stable in 15 the floor 6, and comprises oppositely disposed side walls 8 of concrete and a sloping concrete bottom 9 being lower at the outlet end of the gutter than at the opposite end, and a pair of oppositely disposed bearing shoulders 10 and 11 are provided at the sides of said gutter bottom 9 for supporting the lower reach of the chain conveyor later to be described.

20 Opposed bearing shoulders 12 and 13 will be formed adjacent the shoulders 10 and 11 upon a higher level, and will support the thick concrete blocks 14 which form a partition between the upper and lower levels of said gutter 7.

25 Disposed upon the concrete blocks 14 are the vertically extending trough or gutter side wall blocks 15 which are cemented in place and take care of the side thrust of the endless automatic manure conveyor later to be described.

A transverse shaft 16 is mounted for rotation in the bearings 17 at the discharge end of the manure trough or gutter 7, and a transverse shaft 18 is also rotatably mounted and disposed at the inner end of said trough or gutter 7, being supported in the bearings 19 attached to the adjustable bolts 20 which extend through an end 2 of the barn or stable, and are secured by means of the nuts 20'.

30 Endless conveyor chains or belts 21 and 22 are supported upon sprockets 23 and 24 secured respectively to the transverse shafts 16 and 18, and transversely extending upstanding cross bars 25 are connected between every sixth link of the conveyor chains 21 and 22.

The cross bars 25 and conveyor chains 21 and 22 will drag along the upper portion of the gutter or trough 7 upon the upper surfaces of the heavy partition or bearing blocks 14 with the side wall blocks 15 limiting the outward or sidewise movement of the conveyor. The chains 21 and 22, as they pass through the lower portion of the gutter or trough 7, run along the opposite bearing

shoulders 10 and 11 with the cross bars 25 extending below and into the intermediate depressed gutter bottom 9.

The conveyor will extend through the doorway or opening 3 in the end wall 2 to overlie the elongated concrete pit 4 formed at the end of the barn or stable.

A carrier or receptacle 26 having handles 27 will be disposable in the pit 4, and will be connected with the chains 28 extending up to the overhead crane 29 which is mounted upon the wheel-supported frame 30 upon the overhead track 31 supported upon the vertical supporting standards 32 arranged in spaced relation and leading to any desired portion of the barnyard: 15 adjacent a manure dump pile (not shown), whereby, when the carrier 26 has been filled with manure, the crane 29 will elevate the same from the pit 4 by means of the gear mechanism 33 and operating chain 34. The carrier 26 and the traveling crane 29 then will be either manually or mechanically propelled along the overhead trackway 31 until it reaches the manure dump and the carrier is emptied. The carrier 26 and crane 29 is then run back to a position to overlie the pit 4, and the carrier is again disposed within said pit 4.

The driving mechanism for the automatic manure conveyor includes an enclosed pump jack mechanism 35 which will be positioned within the barn or stable adjacent the discharge end of the automatic manure conveyor, said pump jack having means for supporting an electric motor 36 whose pulley 37 will be connected by means of the belt 38 with the large pulley wheel 39 on said pump jack 35 for operating the same when the motor 36 is energized by electricity from any suitable source of electric current supply. (not shown).

The pump jack 35 includes the usual gearing or gear reduction mechanism (not shown), which is connected by the pivoted arm 40 for oscillating movement in an upward and downward direction. A connecting bar 41 is pivotally connected to the outer end of the arm 40 and is connected at its upper end with an offset pump handle bar 42 formed with oppositely extending terminal arms 43 and 44. The conveyor shaft 16 at the outer end of the conveyor is extended and supports the toothed ratchet wheel 45 thereon. A link 46 is pivotally connected at its opposite ends with the inner end of the arm 44 and with the shaft 16. Angularly disposed, depending ratchet operating levers 47 and 48 are pivoted at 49 to the outer end of the arm 44 and are pivotally connected at their lower ends to the angularly disposed, upwardly extending ratchet operating levers 50 and 51, whose lower ends are pivotally supported upon the conveyor shaft 16.

Oppositely disposed dogs or pawls 52 and 53 are pivotally supported at the junctions of said levers 47 and 48, and the levers 50 and 51, and are adapted to alternately engage the teeth on the ratchet wheel 45 as the pump jack is operated by the electric motor 36, whereby the automatic manure conveyor will be continuously operated when the electric motor 36 is in operation.

From the foregoing description, it will be apparent that an automatic manure conveyor of the hereinbefore described construction having an outwardly sloping bottom and upper surface has been devised and provided for efficiently and effectively removing manure from a barn or stable, and in which construction the operation will be entirely automatic.

While the preferred embodiment of the instant invention has been illustrated and described, it will be understood that it is not intended to limit the scope of the invention thereto, as many minor changes in detail of construction may be resorted to without departure from the spirit of the invention.

Having described the invention, what is claimed as new is:

1. In a barn or stable having a floor with a longitudinally extending gutter or trough formed therein, said gutter or trough including a lower portion formed by transversely opposed longitudinally extending upper and lower steps, transversely extending partition blocks disposed on said upper steps, an endless chain conveyor formed with spaced chains having its upper reach operable on said partition blocks and its lower reach bearing on said lower steps, cross bars connected at spaced intervals between said spaced chains, and driving means for said endless chain conveyor.

2. In a barn or stable having a floor with a longitudinally extending gutter or trough formed therein, said gutter or trough including a bottom and opposed straight side walls, a pair of longitudinally extending transversely opposed lower steps extending upwardly from the bottom adjacent the side walls and a similar pair of upper steps extending from the lower steps and communicating with the side walls transversely extending abutting partition blocks disposed between said upper steps, an endless chain conveyor formed with spaced chains having its upper reach slidably over said partition blocks and its lower reach bearing on said lower steps, cross bars connected at spaced intervals between said spaced chains, a prime mover and intermittent ratchet wheel means actuated by said prime mover for driving said endless chain conveyor.

3. The combination with an animal enclosure having a floor formed with a longitudinally extending gutter including a bottom portion, transversely opposed lower and upper steps projecting upwardly and outwardly from said bottom, a pair of opposed straight walls extending from the inner edges of the upper steps, transversely extending abutting partition blocks disposed between said side walls and seated on said upper steps, of an endless conveyor having a pair of opposed endless flexible members, said flexible members being slidable over the partition blocks and slidably bearing on the lower steps, cross bars carried by said flexible members and driving means for said conveyor including a prime mover, a pumping mechanism actuated by said prime mover and intermittent ratchet means, operatively associated with said pumping mechanism and connected to said conveyor.

4. The combination of claim 3, wherein a pump handle having oppositely extending parallel arms is connected between said pumping mechanism and said ratchet means said means including pivoted intermittently operated pawls.

5. The combination of claim 3, wherein a pit is disposed at the end of said gutter, a carrier removably positioned therein, and a crane and elevated trackway associated with said carrier for elevating the same from said pit when filled with manure from said gutter or trough and for transporting the filled carrier to a predetermined place for emptying.

6. In combination with a barn or stable having a trough formed with an outwardly and downwardly sloping gutter or trough extending

longitudinally thereof including a lower portion formed by opposed upper and lower steps, thickened transversely extending abutting partition blocks disposed between said upper steps, of an endless chain conveyor formed with spaced chains having its upper reach slidable over said partition blocks and its lower reach bearing on said lower steps, cross bars connected at spaced intervals between said spaced chains, driving means for said endless chain conveyor including a gear reduction mechanism and a toothed ratchet and intermittently operated pivoted pawl mechanism, a pump handle having oppositely extending parallel arms connected between said gear reduction mechanism and said ratchet and pivoted pawl mechanism, a pit at the end of said gutter or trough, a carrier removably positioned therein, and a crane and elevated trackway associated with said carrier for elevating the same from said pit when filled with manure from said

gutter or trough and for transporting the filled carrier to a predetermined place for emptying.

7. The subject matter as claimed in claim 6, and said gutter or trough being provided with oppositely disposed side blocks forming side thrust bearings for said conveyor.

NICHOLAS MARTINOVICH.
